(57) **CLAIM**

The ornamental design for a vehicle mirror cover, as shown and described.

DESCRIPTION

FIG. 1 is a front perspective view of a vehicle mirror cover showing my new design mounted on a vehicle;

FIG. 2 is a back perspective elevational view of the cover shown in FIG. 1;

FIG. 3 is an isometric view with the cover in a flattened arrangement;

FIG. 4 is a front side elevational view thereof;

FIG. 5 is a left elevational view thereof;

FIG. 6 is a right elevational view thereof;

FIG. 7 is a top elevational view thereof;

FIG. 8 is a bottom elevational view thereof; and,

FIG. 9 is a back elevational view thereof.

The broken lines shown in all figures are illustrative of environment only and form no part of the claimed design.

The cross-hatching shown in all figures is understood to represent an elastic fabric.
